(57) **CLAIM**

The ornamental design for a bushing for a roll of web material, as shown and described.

DESCRIPTION

FIG. 1 is a rear perspective view of a bushing for a roll of web material;

FIG. 2 is a front perspective view thereof;

FIG. 3 is a front elevation view thereof;

FIG. 4 is a rear elevation view thereof;

FIG. 5 is a right-side elevation view thereof, the left-side being a mirror image;

FIG. 6 is a cross-sectional view taken along lines 6-6 in FIG. 5; and,

FIG. 7 is another cross-sectional view taken along lines 7-7 in FIG. 5.

The design consists of the features of shape and configuration of the portion of the bushing shown in solid lines in the drawings. The portions shown in broken lines do not form part of the claimed design.

1 Claim, 6 Drawing Sheets
